DOOR CONSTRUCTION

Julius L. Byrne, Detroit, Mich.

Application April 14, 1941, Serial No. 388,530

3 Claims. (Cl. 268—51)

The invention relates to doors and refers more particularly to doors of the sliding type operable by linear members.

In doors of the sliding type comprising a plurality of door members or leaves operable by a single linear member, it is desirable at times to disconnect one or more of the door members or leaves from the linear member for movement manually.

The invention has for one of its objects to provide an improved structure by means of which the door members or leaves may be readily connected to or disconnected from the linear member.

The invention has for other objects to provide an improved construction of clamp between the linear member and each door member or leaf; to provide means for operating the clamp from a zone remote from the clamp; and to provide the clamp with guide means engageable with a support for an intermediate portion of the linear member to deflect the support and to thereby avoid interference.

These and other objects of the invention will become apparent from the following description, taken in connection with the accompanying drawings, in which

Figure 1 is a side elevation illustrating a door embodying my invention;

Figure 2 is a cross section on the line 2—2 of Figure 1;

Figure 3 is a diagrammatic view of the door operating system;

Figure 4 is an inside elevation of a portion of the door;

Figure 5 is an enlargement of a portion of Figure 4;

Figure 6 is a top plan view of Figure 5;

Figure 7 is an end view, partly in section, of Figure 5;

Figure 8 is a cross section on the line 8—8 of Figure 5.

My invention is applicable to doors of the sliding type operable by linear members. While the doors are adapted to be used in various structures, such as airplane hangars, factories and warehouses, I have illustrated in the present instance an airplane hangar door which closes one half of the entrance opening and comprises the door members or leaves 1, 2, 3 and 4 of the same widths.

The door members or leaves are preferably arranged within the building in upright position parallel to each other and also transversely offset with respect to each other so that they may

be moved relatively to each other across the entrance opening. When in closed positions, the door members or leaves are relatively extended and their adjacent ends normally overlap. When in open positions, the door members or leaves are arranged side by side, or juxtaposed, and their corresponding ends are in substantial alignment in a plane at right angles to their paths of movement.

Each of the door members or leaves is provided at its bottom with the rollers 5 which support the door member or leaf and are movable over suitable tracks in the floor. Each door member or leaf is provided at its top with the pairs of rollers 6 engaging the depending stems of the T-beams 7 whereby the top of each door member or leaf is guided.

To move the door members or leaves to open or closed positions, I provide the linear member 8 which is adapted to be connected to each of the door members or leaves and is reeved over the series of sheaves 9 and 10 and is connected at one end to the anchor 11 and at the other end to the drum 12. The linear member, as shown is a continuous flexible cable which from its point of connection to the anchor 11 is alternatively reeved over the sheaves 9 and 10. The upper portions 13 of the cable are located above the T-beams 7 and the plate 14 while the lower portions 15 of the cable are located below the plate 14 and preferably midway between the depending flanges of the T-beams 7. There are four lower portions in the present instance with each connected to a different door member or leaf when in operating condition.

The sheaves 10 are stationarily mounted on the framework of the building and the sheaves 9 and the drum 12 are movably mounted on the framework of the building. More particularly, the sheaves 9 and the drum 12 are mounted on the carriage 16 which is movably mounted on the framework of the building and is reciprocable through a path preferably parallel to the paths of movement of the door members or leaves. The carriage is adapted to be moved by an electric motor 17 which is mounted thereon and drives gearing carried by the carriage and meshing with the racks 18 on the framework of the building. The movement of the carriage is in timed relation to the rotation of the drum to compensate for the extent of cable either wound upon or unwound from the drum so that the cable is maintained taut throughout its length at all times.

The construction as thus far described is the

same as that of the J. I. Byrne Patent No. 2,178,136, issued October 3, 1939, which illustrates and describes the construction in detail.

For the purpose of detachably coupling each door member or leaf to the cable, I have provided the structure as illustrated in Figures 4 to 8, inclusive. In detail, 19 is a bracket secured to the inside of each door member or leaf at its top. The bracket is angle shaped and has the plate 20 extending vertically along the inside of the door member or leaf and clearing the adjacent depending stem of the T-beam 7 and the transverse part 21 extending over the door member or leaf. Suitable means, such as the screws 22, extending through the plate secure the bracket to the door member or leaf. The transverse part 21 has integrally spaced top and bottom walls 23 and 24, respectively, and the grip portion 25, which latter is located at the free edge of and integral with the bottom wall. The grip portion is formed with the semi-circular face 26 for engaging a lower portion 15 of the cable 8. The grip portion has at its top the flange 27 which extends toward and is in substantially the plane of the top wall 23. This flange, however, terminates at a distance spaced from the adjacent edge of the top wall sufficient to readily permit the cable to pass therebetween. To cooperate with the grip portion to connect the cable positively to the bracket and thus to the door member or leaf, I have provided the grip member 28 which is in the nature of a bar having along one longitudinal edge the semi-circular face 29 for engaging the side of the cable opposite that engaged by the semi-circular face 26. The grip member is supported on the side portions 30 of the bottom wall 24 and has the lateral projections 31 which extend from the edge opposite the semi-circular face 29 to slidably engage the top and bottom walls 23 and 24 and also the end walls 32 between the top and bottom walls.

The grip member is secured to the link 33 which has the base 34 and the furcations 35. The base is formed with the longitudinally extending slots 36 of a size to receive the bolts 37 which also extend through the grip member and serve to adjustably secure the grip member to the link. The furcations 35 are provided with axially aligned holes for receiving the pin 38 which extends through the link 39 and pivotally secures the two links 33 and 39 together. The link 39 is pivotally connected at its opposite end by the pin 40 to the reach rod 41 which extends longitudinally of the plate 20. The link 39 is also pivotally connected substantially midway between its ends by the pin 42 to an end of the link 43 having the furcations 44 adapted to freely embrace the link 39. The furcations 44 are pivotally connected to the transverse part 21 by the axially aligned pins 45 which extend through the lugs 46 integral with the transverse part. The pins are preferably fixedly secured to the lugs by suitable means, such as the set screws 47.

The construction is such that the clamp for coupling the cable to a door member or leaf is toggle operated, the links 39 and 43 forming the toggle. It will be noted that the pivot pin 42 occupies a position with its axis above the line connecting the axes of the pivot pins 38 and 45 when the reach rod 41 has been moved to its uppermost position to move the grip member to clamping position. As a result, the operating mechanism is locked from accidental disengagement.

For the purpose of normally limiting the move-

ment of the grip member away from the grip portion so that the cable cannot become accidentally disengaged from the clamp, the link 33 has the upright flange 48 which is normally engageable with the edge of the top wall 23 when the grip member is moved away from the grip portion. However, to enable initial engagement of the cable with the clamp, or to enable its replacement, if desired, the link 33 may be permitted to lower by releasing the nuts on the bolts 37 sufficiently to allow the flange 48 to clear the top wall 23 and pass therebeneath. To enable the lowering of the link and also to enable operating the linkage, the bottom wall 24 is formed with a central slot or opening.

For the purpose of relieving the bolts 37 from shearing stress and also more positively positioning the grip member 28 longitudinally upon the link 33, a shim or a plurality of shims 49 may be placed between the adjacent end of the grip member and the upright flange of the link, these shims preferably having depending projections 50 at their ends for extending at the outer sides of the base 34 of the link 33 so that accidental endwise disengagement is avoided.

The reach rod 41 extends through the hole 51 formed at the lower end of the plate 20 and is pivotally connected at its lower end to the lever 52 intermediate the ends of the latter. The lever is floatingly mounted upon the bracket, it being pivotally connected intermediate its ends to the lower end of the link 53, the upper end of which is pivotally connected to the lower end of the bracket. The distance between the pivot connecting the reach rod to the lever and the adjacent end of the lever is preferably the same as the distance between the pivot connecting the floating link to the lever and the adjacent end of the lever. To enable an operator on the floor to operate the clamp, the ends of the lever 52 have secured thereto the linear members 54, which are preferably tiller ropes, and these linear members are provided at their lower ends with the handles 55 which may be readily grasped by the operator on the floor. The tiller ropes are preferably guided on the inside of the door member or leaf by the keepers 56.

To support the lower portions 15 of the cable so that they will extend substantially uniformly in a horizontal direction, there are the supporting rollers 57 which are yieldably held upwardly against the lower portions intermediate their ends. Each supporting roller is rotatably mounted upon a bracket 58 which is fixedly secured to an end of the spring leaf 59, the opposite end of which may be fixedly secured to a head flange of one of the T-beams 7, or to the plate 14. To avoid interference with a door member or leaf during its movement, the transverse part 21 of each bracket is formed at its free end with the downwardly extending guide portion 60 engageable with the roller to deflect the same away from the cable by moving it downwardly. The guide portion is preferably V-shaped and has inclined ends to gradually deflect the roller. With this construction, it will be seen that the roller cannot interfere with the door member or leaf during its movement.

What I claim as my invention is:

1. In a device for detachably gripping a linear member, a bracket having a grip portion engageable with the linear member, a grip member carried by and movable relative to said bracket and engageable with the linear member, said grip

member being cooperable with said grip portion to grip the linear member, a link pivotally mounted on said bracket, a reach rod, and a second link pivotally connected at its opposite ends to said grip member and reach rod and intermediate its ends to said first mentioned link, the pivotal connection intermediate the ends of said second link being movable from one side to the other of the line between the pivotal mounting for said first mentioned link and the pivotal connection to said grip member.

2. In a device for detachably gripping a linear member, a bracket having a grip portion engageable with the linear member, a grip member movable relative to said bracket and engageable with the linear member, said grip member being cooperable with said grip portion to grip the linear member, and means carried by said bracket for operating said grip member, said means comprising a reach rod guided by said bracket and operatively connected to said grip member, and a

lever carried by said bracket and pivotally connected intermediate its ends to said reach rod.

3. In a device for detachably gripping a linear member, a supporting member having a grip portion engageable with the linear member, a grip member mounted on and movable relative to said supporting member toward and away from said grip portion and engageable with the linear member, a member for moving said grip member provided with a stop engageable with said supporting member to limit movement of said grip member away from said grip portion to avoid accidental movement of the linear member from operative relation to said grip portion and grip member, means for adjustably securing said moving member to said grip member to provide clearance between said stop and supporting member, and means carried by said supporting member for operating said moving member.

JULIUS I. BYRNE.
